UNITED STATES PATENT OFFICE.

OSBORN B. ROBERTSON, OF GONZALES, TEXAS.

GEARING FOR GIN-SAW CLEANERS.

1,249,504.

Specification of Letters Patent. Patented Dec. 11, 1917.

Application filed June 4, 1917. Serial No. 172,712.

To all whom it may concern:

Be it known that I, OSBORN B. ROBERTSON, a citizen of the United States, residing at Gonzales, in the county of Gonzales and 5 State of Texas, have invented a new and useful Gearing for Gin-Saw Cleaners, of which the following is a specification.

The present invention relates to improvements in a gearing for gin saw cleaners, 10 and is particularly an improvement over the gearing for gin saw cleaners disclosed in Patent No. 1,215,413, granted February 13, 1917.

It is the object of the invention to provide simple and effective means for gradually starting and accelerating the rotation of 15 the gin saw cleaner as it is moved into operative position to clean the saws, to avoid the sudden rotation of the cleaner and to 20 speed it up as it moves into engagement with the saws.

With the foregoing and other objects in view, which will appear as the description 25 proceeds, the invention resides in the combination and arrangement of parts and in the details of construction hereinafter described and claimed, it being understood that changes in the precise embodiment of the 30 invention herein disclosed can be made within the scope of what is claimed, without departing from the spirit of the invention.

The invention is illustrated in the accompanying drawing, wherein the figure is a 35 fragmental elevation of a gin including the cleaner, and gearing therefor.

The numeral 1 designates the drive shaft 40 of the saws 2, and 3 indicates the cleaner for the saws, of the construction shown in said patent, or the patent on gin saw cleaner No. 1,140,669. The cleaner 3 is mounted on a shaft 4 which is moved toward and away 45 from the shaft 1 and saws 2, by any suitable mechanism, such as disclosed in the first mentioned patent, to move the cleaner into and out of engagement with the saws.

The gearing embodies a section wheel 5 secured upon the shaft 1, and composed of metal, fiber, or other suitable material, said wheel being provided with a V-shaped periphery 50 providing opposite beveled surfaces 6. A friction wheel or pinion 7 of smaller diameter than the wheel 5 is feathered upon the shaft 4 or otherwise mounted to slide thereon and rotate therewith, and this wheel 55 7 is provided with a conical or beveled surface 8 at one side. A wheel 9 of smaller di-

ameter than the wheel 7 has a conical or beveled surface 10 confronting the surface 8 and the smaller portions of the wheels 7 and 9 are attached together in any suitable manner, so that said wheels rotate together as a unit.

The wheels 7 and 9 are shifted longitudinally when removed from the wheel 5, by means of a coiled expansion spring 11 surrounding the shaft 4 and confined between the wheel 7 and a collar 12 on said shaft, a stop 13 being mounted on a shaft to limit the movement of the wheels 7 and 9, the wheel 9 60 contacting with said stop. 70

The operation of the gearing is as follows: When the shaft 4 is moved to bring the cleaner into engagement with the saws, for cleaning the latter, the shafts in being moved toward one another relatively, will 75 cause the marginal portion of the wheel 7 to overlap one beveled surface of the wheel 5 which frictionally engages the beveled or conical surface 8 of the wheel 7. The frictional engagement of said wheel 7 with the 80 wheel 5, will cause the wheel 7 to be rotated by the wheel 5 which continues to rotate during the operation of the saws. Consequently, the wheel 7 will be given a slow initial movement by the wheel 5, thereby 85 starting the rotation of the cleaner, and as the cleaner is moved into operative position, the wheel 7 will be forced against the tension of the spring 11 by the cam action between the beveled surface 8 and the corresponding beveled surface 6 of the wheel 5, it 90 being noted that as the shaft 4 is moved nearer to the shaft 1, the point of contact between the wheels 5 and 7 will shift closer to the axis of the wheel 7, thereby increasing 95 the ratio of rotation between said wheels, and accelerating the rotation of the wheel 7 and cleaner. When the cleaner reaches operative position, the wheel 9 is brought into engagement with the other beveled surface 6 of the wheel 5, the V-shaped edge of the wheel 5 having a wedge fit within the V-shaped annular groove between the beveled surfaces 8 and 9, whereby the cleaner will now be rotated at its greatest speed, and 100 faster than the saws, to clean them. When the cleaner is moved away from the saws, the gearing will be restored to normal position, as seen in the drawing. The wheels 7 and 9 constitute a friction pinion having an 105 annular V-shaped groove, one inclined wall being of greater height than the other for

the engagement of the wheel 5 therewith, and to shift the pinion longitudinally as it is moved completely into engagement with the wheel 5.

5 Having thus described the invention, what is claimed as new is:

1. A gearing embodying a wheel and a pinion movable toward and away from one another, one of them being shiftable and held yieldingly against shifting movement, the pinion having opposite beveled surfaces, and the wheel having opposite beveled surfaces, one of which is movable into engagement with one of the beveled surfaces of the pinion when the pinion and wheel are moved toward one another, to start and accelerate the relative rotation of said wheel and pinion, the other beveled surfaces thereof being movable into engagement when the movement of said wheel and pinion toward one another is completed.

2. A gearing embodying a wheel and a pinion movable toward and away from one another, one of them being shiftable yieldably, the wheel having a V-shaped periphery providing opposite beveled surfaces, and the pinion having a V-shaped groove providing confronting beveled surfaces for the engagement of the beveled surfaces of the wheel, said groove and wheel being offset in different planes, one of said surfaces of the pinion being extended for the engagement therewith of the corresponding beveled sur-

face of the wheel during the movement of the wheel and pinion toward one another to start and accelerate their relative rotation and shift them into position for the engagement of the other beveled surfaces also.

3. A gearing embodying two shafts movable toward and away from one another, a wheel upon one shaft to be rotated thereby and having a V-shaped periphery providing opposite beveled surfaces, a pinion slideable upon the other shaft to rotate it, the pinion having an annular V-shaped groove providing confronting beveled surfaces for the engagement of the beveled surfaces of said wheel, a spring moving the pinion so that one beveled surface of the pinion is engaged by the corresponding beveled surface of the wheel before the others, during the movement of the shafts toward one another, the first mentioned beveled surface of the pinion being extended to be engaged by the corresponding beveled surface of the wheel during the movement of the shafts toward one another, to start and accelerate the rotation of the second mentioned shaft.

In testimony that I claim the foregoing as my own, I have hereto affixed my signature in the presence of two witnesses.

OSBORN B. ROBERTSON.
